UNITED STATES PATENT OFFICE.

GEORGE MARCROFT, OF PROVIDENCE, RHODE ISLAND, ASSIGNOR TO UNIVERSAL
WINDING COMPANY, OF PORTLAND, MAINE, A CORPORATION OF MAINE.

COMPENSATOR DEVICE FOR CONTROLLING THE UNWINDING OF YARN, THREAD, OR SIMILAR MATERIALS.

1,156,913.

Specification of Letters Patent.

Patented Oct. 19, 1915.

Application filed February 24, 1914. Serial No. 820,600.

To all whom it may concern:

Be it known that I, GEORGE MARCROFT, a citizen of the United States, residing at Providence, in the county of Providence and State of Rhode Island, have invented certain new and useful Improvements in Compensator Devices for Controlling the Unwinding of Yarn, Thread, or Similar Materials, of which the following is a specification.

My invention relates to compensator-devices for controlling the unwinding of yarn, thread or similar materials in delivering the same to winding machines or other textile apparatus.

The object of my improvement is to provide means for controlling the unwinding or unreeling of the yarn or thread from spools, skeins or other supplies to maintain a smooth, even delivery thereof, and prevent snarling, kinking, straining or breaking of the material.

The invention is fully described in the following specification, illustrated by the accompanying drawings, in which like reference characters designate like parts.

In the drawings:—

Figure 1 is a view of a usual style of bobbin-winder showing my invention applied thereto; and Figs. 2 and 3 are enlarged views showing structural details of the device.

Referring first to Fig. 1, I have here illustrated a well-known type of winding machine comprising, essentially, the main frame A mounted on a base or bed B and carrying bearings for a series of horizontal winding-spindles C. Arranged parallel with each winding-spindle C is a transverse-bar D, also mounted in bearings in the frame A, and carrying a yarn- or thread-guide E adapted to be reciprocated longitudinally of the spindle. The yarn y is wound on the bobbin b while being traversed by the guide E and the supply is here illustrated as being delivered from a rotating spool F. The above named elements are all common to usual types of winding machines and it is to be noted that they are here illustrated merely for convenience in showing the method of putting my new device into practice. It is therefore called to attention that the present invention is adapt-

ed to be applied to other varieties of textile apparatus and can also be used with different forms of supplies such as hanks or skeins held on swifts, reels or runners.

The supply spool F here illustrated may be held by any suitable arrangement to adapt it to rotate to unwind the yarn and as shown in the drawing is mounted on a "live" spindle G. The spindle G is rotatable in bearings h, h' formed on a bracket H fastened to rods h', h', the latter being supported on the legs I which serve as standards for the base B of the winding machine. Fast on the spindle G is a grooved collar or brake-wheel g through which the rotation of the spindle and spool F is controlled. Any suitable means may be used to apply friction to the brake-wheel g to resist the rotation of the spool, but as here illustrated I prefer to employ the simple expedient of a strap or cord g' wrapped around the wheel and carrying weights g² suspended at its end. By adding to or subtracting from the number of weights g² the proper friction can be applied to prevent the spool F from rotating too freely under the draft of the yarn y and to apply the proper tension to the material. From the spool F the yarn leads up through a stopping-lever J which serves as an element of the controlling-mechanism of the winding machine, but is not here shown or described in detail since it forms no part of the present invention. From the stopping-lever J the yarn leads up through a guide or over a grooved wheel or pulley k which is mounted on the end 90 of a pivoted compensator- or controller-arm K. The means for controlling the compensator-arm K forms the essential feature of the present invention and will now be described in detail.

Mounted on the top of the frame A of the machine are a series of yokes or inverted U-shaped brackets L which support a longitudinally-extending rod or bar M. The rod M is preferably rectangular in cross-section and serves as a support for the vertical brackets or standards N which carry the compensator-arms K. Only one bracket L and arm K are here shown, but it will be understood that these are arranged in series corresponding to the number of wind-

ing-spindles C projecting from the frame A. The standard N is held on the rod M by any suitable means, such as the set-screw n shown in Fig. 2, and at its upper extremity is formed with a suitable bearing for the pivot-pin k' of the arm K, see Fig. 1. Preferably, the arm K is constructed of round rod or heavy wire and is passed through a sleeve O having an offset hub o for the pivot-pin or stud k' . A set-screw o' serves to hold the arm K in its bearing in the sleeve O while allowing longitudinal adjustment thereof to provide for altering the position of the guide or pulley k in relation to the pivot of the arm. Adapted to be slidably adjusted on the arm K are two yoke-shaped clamp-members P, P' held in place by the set-screws p , p' . Fastened to the clamps P, P' are two coiled springs S, S' arranged at either side of the pivot k' of the arm K. The lower ends of the springs S, S' are secured to the right-angled portions r of two vertically-adjustable, L-shaped rods R, R, see Fig. 3, which are held on the standard N. Referring to Fig. 2, the rods R are preferably fitted to slide in holes n' , n'' in the base n^2 of the standard N and are held in place by the set-screws r' , r'' . The two springs S, S' act in opposition to each other to control the movement of the compensator-arm K, and preferably the spring S' is of slightly greater resilience than the spring S.

The operation of the complete device is as follows: The yarn y is led from the spool F through the guide at the end of the stopping-lever J and thence up over the wheel or guide k on the compensator-arm K. From the guide k the yarn leads down through the thread-guide E to the bobbin b and is wound thereon in the usual manner. When the winding-spindle is first started there will be a greater resistance to the delivery of the yarn from the spool F than after the spool has once commenced to rotate. That is to say, it is first necessary to overcome the inertia of the spool F and its spindle G, and to compensate for this abnormal resistance to delivery as the yarn starts to unwind the arm K will be drawn downwardly against the tension of the spring S'. Now, after the spool F starts to turn it will gain momentum very quickly and is liable to overrun so that more yarn is given off than required. The arm K then acts to compensate for this excessive rotation of the spool by swinging upwardly under tension of the spring S' to take up the slack in the yarn and prevent it from kinking or snarling between the spool and the bobbin. At this point the auxiliary spring S comes into play to gradually check the upward movement of the arm K and prevent it from rebounding or springing back too far. In other words, the spring S acts as a shock-absorber

to control the upward movement of the arm K, and prevent the guide k from jerking against the loop in the yarn. Through this compensating or balanced action of the two opposed springs S and S' the arm K is controlled to act with a smooth, even movement so that the yarn is not unduly stretched or strained and consequently there is less liability of breaking it. Not only does the compensating action of the two springs S, S' tend to relieve the strain on the yarn, but it also serves to neutralize any excessive tension of draft during irregularities in the rotation of the spool. For instance, if the yarn happens to catch on the spool during the unwinding, or if its delivery therefrom is restricted or impeded in any way, the arm K will be drawn downwardly to stretch the spring S'. As the spring S' is lengthened under this action of the arm K its tension increases gradually until the pull on the yarn becomes sufficient to free it from the spool and the arm K will then swing upwardly again to take up the extra slack. Now, as the yarn becomes suddenly free from the spool it will have a tendency to give an added impulse of rotation to the latter which is liable to cause the spool to overrun and deliver more yarn than required. This tendency of the yarn to jerk on the spool is nullified by the action of the buffer-spring S. That is to say, the arm K is restrained from a sudden rebound or upward movement and hence the slack is taken up so gradually that the yarn will not act on the spool to still further accelerate its speed of rotation. As the yarn winds from the small diameter up to the large diameter on the tapered nose of the bobbin and back again, there is a constant change in the draft on the yarn. That is, more yarn is taken up at the point where the yarn winds on the large diameter than where it is winding on the extreme point of the bobbin and as the thread-guide reciprocates very rapidly these changes in the draft are quite sudden. During these intermittent variations in the pull on the yarn the compensator-arm K plays up and down continuously, and by taking up and paying out the slack overcomes the jerking action on the spool. By regulating the movement of the arm K in both directions a smooth, sensitive response is made to the variations in the tension of draft on the yarn and the rotation of the spool is controlled so delicately that its speed remains practically constant. Whenever any abnormal resistance to the delivery of the yarn is encountered, the pull on the spool is increased so gradually that instead of binding the yarn more firmly to the spool there is a tendency to relieve it therefrom and therefore the yarn becomes freed more quickly and easily. After the yarn is once freed the arm K takes up the slack only in proportion

to its relief so that no sudden strain is imposed on the material and no added impulse is given to the rotation of the spool.

By adjusting the clamps P, P' toward or 5 away from the pivot k' of the arm K, the springs S, S' can be balanced to control the arm as best suited to the conditions of the winding and the tension of the springs may be varied according to the requirements of 10 different materials being unwound by adjusting the rods R, R up and down in their slots.

I am aware that spring-operated arms have previously been used in the art for 15 controlling the delivery of yarn from rotating spools or other supplies. Heretofore, however, the control of the arm has been in one direction only, and as far as I am aware it has never been proposed to employ a 20 shock-absorbing element or buffer-spring to prevent excessive movement of the arm under action of its main spring. It is thought that the present arrangement is the first disclosure of a means for balancing the compensator-arm or lever against quick movement under sudden release of tension on the 25 yarn, and it is believed that this construction shows meritorious improvement in the art.

30 Various modifications might be made in the form and structure of the parts of my device without departing from the spirit or scope of the invention; therefore, without limiting myself to the exact embodiment 35 shown and described,

What I claim is:—

1. In a compensator-device for controlling the unwinding of yarn, thread or the like, the combination with a pivoted arm, of a 40 guide at the end of said arm over which the yarn draws, a spring engaging the arm on one side of its pivot to resist its movement under the influence of increasing tension of draft on the yarn, and a second 45 spring engaging the arm on the opposite side of its pivot to resist its movement under action of the first spring to prevent the arm from rebounding when the tension on the 50 yarn is relieved.

50 2. In a compensator-device for controlling the unwinding of yarn, thread or the like, the combination with a pivoted arm adapted to be operated upon by the running yarn, of a spring secured to said arm at one

side of its pivot to control its movement 55 under the action of increasing tension on the yarn, a second spring secured to the arm on the opposite side of its pivot to check its movement under the action of the first spring, and means to adjust said springs in 60 relation to the pivot of the arm to regulate the balance of the springs.

3. In a compensator-device for controlling the unwinding of yarn, thread or the like, the combination with a pivoted arm 65 adapted to be operated upon by the running yarn, of a spring connected to said arm at one side of its pivot, a second spring connected to the arm on the opposite side of its pivot to check the movement of the arm 70 under the action of the first spring, means to adjust the connecting-means for the springs along the arm in relation to its pivot, and means to vary the tension of the 75 springs.

4. In a compensator-device for controlling the unwinding of yarn, thread or the like, the combination with a standard, of an arm pivoted on said standard to adapt it to be operated upon by the running yarn, 80 springs connected to the arm on the opposite sides of its pivot, means to adjust the points of connection of the springs along the arm, rods connected to the opposite ends of the 85 springs, and means for securing the rods to the standard to allow longitudinal adjustment thereof to vary the tension of the springs.

5. In a compensator-device for controlling the unwinding of yarn, thread or the 90 like, the combination with a standard, of an arm pivoted on said standard to adapt it to be oscillated from variations in the tension of the yarn operating thereupon, springs 95 connected with said arm on opposite sides of its pivot, rods mounted to slide in bearings on the standard and connected to the opposite ends of the springs, and means to secure the rods in their bearings to allow adjustment thereof to vary the tension of the 100 springs.

In testimony whereof I affix my signature in presence of two witnesses.

GEORGE MARCROFT.
